UNITED STATES PATENT OFFICE.

CHRISTIAN FREDERIK HILKIER, OF COPENHAGEN, DENMARK.

THERMOSTAT.

SPECIFICATION forming part of Letters Patent No. 403,937, dated May 28, 1889.

Application filed December 29, 1888. Serial No. 294,977. (No model.) Patented in Denmark April 20, 1886, No. 474, and in Norway October 22, 1887, No. 724.

To all whom it may concern:

Be it known that I, CHRISTIAN FREDERIK HILKIER, of Copenhagen, in the Kingdom of Denmark, have invented certain new and useful Improvements in Thermostats and Thermostatic Contact Devices, (for which I have received Letters Patent in Denmark April 20, 1886, No. 474, and in Norway October 22, 1887, No. 724;) and I do hereby declare the following to be a full, clear, and exact description of the invention, such as will enable those skilled in the art to which it appertains to make and use the same.

My invention relates to the general class of thermostats, but is more particularly designed for use as an electrical contact device opened or closed by rise or fall of temperature, according to the nature of its intended use.

The invention consists in the construction of the thermostat, and in the combination and arrangement of parts, substantially as hereinafter fully described and claimed.

In the accompanying drawings, which form part of this specification, Figure 1 is a plan view of the thermostat alone. Figs. 2 and 3 are sectional views of two different forms of the thermostat, the former to operate by rise and the latter by fall of the temperature. Fig. 4 is a sectional elevation, and Fig. 5 is a plan, of the thermostat and contact-making device complete for indicating electrically a rise in temperature. Fig. 6 is a sectional view, on a larger scale, of the complete device for electrically indicating a fall in temperature. Fig. 7 is a section, and Fig. 8 an elevation, of the thermostat and push-button combined. Fig. 9 is a section showing a thermostat located within the cover of a push-button. Figs. 10 and 12 are side elevations of simpler contact arrangements. Figs. 11 and 13 are details.

In its simplest form my improved thermostat consists of a hermetically-sealed flat case or chamber composed of a sheet-metal front, *a*, and sheet-metal back *b*, soldered together at the edge, and a stem or filling-tube, *c*. The back *b* is dished to form the chamber. The front *a* is made of spring metal, for which purpose I prefer thin hard-rolled silver, both on account of its high thermal conductivity

and because it is well adapted to resist oxidation by the contained fluid. It is bulged forcibly inward or outward, according to its intended use respectively as a maximum or minimum temperature indicator. The enclosed chamber is filled according to requirement entirely or partly with a suitable fluid, which has its boiling-point or point of ebullition at the temperature at which the contact is to be made. An excellent fluid, which allows a predetermined adjustment of the apparatus to any temperature between 0° and 100° centigrade, is ammonia-water.

After filling, the tube *c* is pinched together and soldered, and for convenience I prefer to solder to it a wire, *d*, for convenience of connection to the binding-screw *e* of the bed-plate *f*. The bed-plate *f* has a recess, *g*, under the thermostat, and into this extends a metal strip, *h*, having a contact-point, *i*, the strip *h* being connected to the other binding-post, *k*. Recess *g* is entirely covered by the thermostat, and hence no dust or dirt can obtain access to foul the contact-surfaces, which therefore will be always reliable, no matter how dirty or dusty the fixture itself may become from the circumstances of use or location.

As a maximum-indicator, the device in filling is arranged with the resilient center of the front *a* bulged inwardly at temperatures below the maximum determined on, as in Figs. 2 and 4, and when the temperature rises the contained fluid expands and forces the concave front *a* outwardly. As the latter passes the normal plane, it snaps outwardly past such normal plane by its own resiliency, and thus affords a means of effecting a good firm contact.

As a minimum-temperature indicator, on the other hand, the device in filling is so arranged that the resilient or spring center of the front *a* bulges outwardly at temperatures above the predetermined point, and the attainment by the fluid in the chamber of that temperature causes it to sufficiently contract to permit the flattening of the convex front *a*, which thereupon snaps inwardly beyond the normal plane, in a manner similar to that previously described. This resilient or snap-

ping action is peculiar and important, being sudden and affording a most reliable movement for effecting contact, and gives a comparatively wide range of adjustment. Of course in the case just described the contacts will be arranged so as to be closed upon the inward movement of the spring-front *a*.

By these two modifications of form I am able to construct the thermostat to fill any of the requirements for which thermostats may be wanted.

If the apparatus is to be used both as thermostat and push-button, it is modified into the form shown at Figs. 7 and 8, where the front *a*, while of larger size, is shaped as before; but the sheet-metal back *b* is deepened and provided with button or projection *m*, so that pressure upon the latter bends in the back *b* and causes the front *a* to act as if the contained fluid had expanded.

The modified push-button and thermostat shown in Fig. 9 is intended for the convenient stowage of the thermostat in rooms and other places where it is not to be seen. The cover *p* not only hides it from view, but also protects it from dust and unauthorized meddling. The one cover *p* incloses the push-button *g* and the thermostat *a b*, and the circuit is arranged so that either may effect a closure.

Obviously the thermostat may be made with both its back and front resilient, or so that both may participate in the expansive or contractile movement imparted by the contained fluid. The mere peripheral shape is unimportant; but I prefer the circular-disk form shown as being the cheapest and simplest.

Two simple, practical, and cheap modifications are shown by Figs. 10 and 12, and 11 and 13, respectively. In Figs. 10 and 12 I take two of the thermostatic disks *a b*, each having, besides its filling-tube *c*, a rod, *r*, fixed to it. The two are laid with their fronts *a* facing, and are tied or bound together after interposing between them an insulating-disk, *s*, having its center portion cut out, as shown in Fig. 11. Increase of temperature causes the normally-inwardly bulged fronts *a* to expand outwardly and firmly snap into contact, thus closing the circuit. In Fig. 12 but one thermostatic disk *a b* is employed, having tube *c* and rod *r*. Facing the front *a* is a contact-

plate, *t*, Fig. 13, mounted on a bar, *v*, and the whole bound together with the insulating-disk *s* between, as before.

The peculiar action of the movable side of the thermostat possesses two advantages. In the first place, as has already been described, the bulged metal receives a motion far in excess of what it would receive were it not for the particular construction whereby its own elasticity carries it to a point beyond the normal plane. This motion occurs with a sudden snap, owing to the construction, and gives a sharp sound, which is quite loud, and in this respect the sound serves as a means of detecting a faulty contact in testing the instruments.

I am well aware that it is not new to construct a thermostat of two plates of metal in the form of a box, nor is it new to construct such a box with one of its sides or faces convex or concave; but so far as I am aware it has never heretofore been proposed to forcibly bulge one of the faces in such manner as to make it resilient and impossible to maintain in a normal plane, so that it must occupy a position to either one side or the other of such normal plane.

I claim as my invention—

1. A thermostat comprising a metallic hermetically-sealed chamber containing an expansive and contractile fluid, and having one or more of its walls constructed of spring metal having a portion thereof sprung out of its normal plane and adapted in operation to spring past such normal plane in both directions, substantially as described.

2. A thermostat comprising a flat disk-shaped chamber hermetically sealed, composed of a cup-shaped back and a flat front soldered together, the front being of spring metal, and having a portion thereof sprung out of its normal plane and adapted in operation to spring past the normal plane, substantially as described.

In witness whereof I have hereunto signed my name in the presence of two subscribing witnesses.

CHRISTIAN FREDERIK HILKIER.
